UNITED STATES PATENT OFFICE.

VERNON A. JOY, OF NEW YORK, N. Y.

HAIRPIN BOX.

Application filed January 2, 1924. Serial No. 623,852.

This invention relates to boxes or containers for hair pins or similar articles.

Considerable inconvenience and loss has heretofore been experienced by retailers and salesmen in the handling of hair pins in boxes for the reason that a customer, in examining the hair pins, upon opening the box, would frequently spill the hair pins out of the box, and considerable time would be required for restoring the same. Securing the hair pins in bundles for the purpose of overcoming this difficulty is not satisfactory for the reason that a customer cannot satisfactorily examine the hair pins when in bundles, and if a bundle is broken to give the customer a chance to examine a single hair pin, the pins cannot again be bundled by the salesman.

The objects of this invention are to provide a hair pin box which is so made as to support a plurality of hair pins within the box without making it necessary to first secure the hair pins together in bundles, and which will permit the ready removal and replacing of individual hair pins without in any way impairing the ability of the box to retain the other pins; also to improve the construction of hair pin boxes in other respects hereinafter specified.

30 In the accompanying drawings:

Fig. 1 is a face view of a hair pin box embodying my invention, the box being shown open to display the pins.

Fig. 2 is a face view of half of the box, one of the pockets of the box being partly broken away.

Fig. 3 is a transverse sectional elevation of a closed box.

Fig. 4 is a transverse sectional plan view thereof.

In the particular embodiment of the invention shown in the drawings, the box employed is made in two parts or halves A and B, which are connected by means of a flexible strip or band C forming a hinge upon which the two parts of the box may swing so that their open faces come together to close the box. Each part of the box includes a back portion or wall 5 having end walls 6 and 7, and side walls 8 and 9 connected therewith, the two side walls 9 of each of the halves of the box being connected by means of the flexible strip C. It will be understood that the particular form of box shown is not by itself a part of my

invention, and other kinds of boxes may be used without departing from this invention.

Each of the halves of the box shown is provided with a plurality of pockets or hair pin retaining devices D which are so formed that the side of a pocket or device may be engaged by the hair pins when the same are in their normal positions. In the particular construction shown in the drawings, the pockets or hair pin retaining devices are in the form of tubes of substantially rectangular cross section, preferably made of paper, card board or the like, and these tubes are secured against the rear wall of the box, preferably in such a manner that the front face of each tube will not extend outwardly beyond the side and end walls 6, 7, 8 and 9 of each part of the box. These tubes may, if desired, be of different lengths, as shown in the drawings, in order to adequately display hair pins of different lengths.

In the use of the box described, each tube is intended to contain a group of hair pins which, however, are not bundled, but loosely placed into the tube. This is done by compressing the ends of the hair pins toward each other and then inserting the group into the tubes or pockets. Upon releasing pressure on the ends of the hair pins, these ends will spring outwardly away from each other, due to the inherent spring action of each of the hair pins, and the ends or sides of the hair pins will thus engage the hair pin retaining device or tube D yieldingly but with sufficient force to prevent a group or bundle of hair pins from being accidentally moved out of the retaining device. In the case of the particular construction shown, the tubes with the hair pins in place there-

in are then glued or otherwise secured to the back 5 of the box. Consequently a customer in carelessly opening a box of hair pins will not cause the spilling of the hair pins owing to the fact that all of the pins are frictionally held in their retaining devices or pockets and at the same time any of the pins can be removed from the retaining devices and examined by the customer without in any way impairing the holding action of the pockets or retaining devices upon the remaining hair pins, and the pin which has been removed can be restored without any difficulty and without in any way changing the appearance of the package.

Another feature of the box shown in the accompanying drawing is that the end walls 6 and 7 of the box are so positioned with reference to each other and with reference to the pockets or pin retaining devices D that if the pins should accidentally be slipped lengthwise in the package, as may, for example, happen if the end wall 6 of the box is subjected to a severe shock or blow, the pins will strike the end wall 6 before the free ends of the pin become disengaged from the pockets or retaining devices D. In order to obtain this result the distance between the end walls 6 and 7 must be less than the combined length of a retaining device and the hair pins contained therein. By means of this additional feature, the accidental spilling of pins from the pin retaining devices is practically eliminated. In Fig. 2 a bundle of pins is shown in its outer position in which the end of the bundle engages the end wall 6 and it will be seen that the pins are still retained in their pocket or holding device.

By means of the construction described the spilling of hair pins from boxes which has heretofore been a troublesome factor in the selling of hair pins is practically eliminated and at the same time a customer is given the opportunity of examining individual hair pins before making a purchase, without in any way damaging the package. The use of a retaining device for yieldingly engaging the sides of the hair pin is particularly effective if the retaining device is supplied with a group of hair pins containing as many hair pins as can be conveniently crowded into the retaining device since by crowding the hair pins into the device, the group of pins acts substantially like a single unit in that the pins will not tend to move relatively to the group of pins unless positively pulled out. Consequently individual pins, whose resiliency may not be such as to cause the sides thereof to exert much pressure against the retaining device, will nevertheless be held against spilling out of the box.

I claim as my invention:

1. A display device for hair pins which comprises a supporting form, and a plurality of enclosures for hair pins supported thereby, each of said enclosures being shorter than the hair pins to be supported thereby, and of approximately uniform widths in cross section, said width being slightly less than the normal distance between the free ends of the arms of the pins to be supported therein, whereby the pins must have their arms compressed somewhat to be inserted in

the enclosures and when so inserted will be frictionally held therein by the spring pressure of the arms against the sides of the enclosure. 60

2. A hair pin box including a back, and side and end walls, and a plurality of substantially tubular pockets secured to said back, each of said pockets being of such size as to receive the ends of a plurality of hair pins and to engage the sides of said pins to hold the pins in place, said end walls being so spaced as to engage a group of hair pins 65 when the same is moved lengthwise out of said pockets and prevent the sides of the pins from moving out of engagement with said pockets, whereby the removal of the hair pins as a group is prevented. 70

3. A display device for hair pins which comprises a box having an open face, said box having in its interior a plurality of containers extending closely adjacent and parallel to the open face of the box in the same direction from adjacent one end, each of a length less than the length of the pins to be inserted therein and terminating from the opposite box end a distance slightly less than the length of the pins to be inserted therein, whereby the pins in each container will be normally confined therein and may be removed only by first flexing through the open face of the box those ends of the pins which project from the containers. 80 85

4. A display device for hair pins which comprises a box having an open face, said box having in its interior a plurality of containers extending closely adjacent and parallel to the open face of the box in the same direction from adjacent one end, each of a length less than the length of the pins to be inserted therein and terminating from the opposite box end a distance slightly less than the length of the pins to be inserted therein, whereby the pins in each container will be normally confined therein and may be removed only by first flexing through the open face of the box those ends of the pins which project from the containers, the widths of the containers being slightly less than the normal distance between the free ends of the arms of the pins to be inserted therein, whereby the pins must have the free ends of their arms compressed together somewhat before insertion into the containers with their loop ends projecting from the containers, and when so inserted will be frictionally held therein by the spring pressure of the arms against the sides of the enclosure. 90 95 100 105 110
